UNITED STATES PATENT OFFICE.

JOSEPH L. HILLER, OF MATTAPoisETT, MASSACHUSETTS.

DESIGN FOR A CRUSHER-MACHINE CASING.

41,097.

Specification for Design.

Patented Jan. 17, 1911.

Application filed October 11, 1910. Serial No. 586,562. Term of patent 14 years.

To all whom it may concern:

Be it known that I, JOSEPH L. HILLER, a citizen of the United States, residing at Mattapoisett, county of Plymouth, and State of Massachusetts, have invented a new, original, and ornamental Design for Crusher-Machine Casings, of which the following is a specification, reference being had to the accompanying drawing, forming part thereof.

The figure is a perspective view of the casing.

The material and essential features of the design reside in the casing having substantial counterpart or similar sections 1, 2, having the sloping or inclined edges 3, 4, and

the intermediate arched section 5. Another feature of distinction is in the raised lateral portions 6. The opposite side of the machine is a substantial counterpart of that shown in the drawing in so far as the essential features referred to are concerned.

The design as a whole presents an ornamental, attractive and distinctive pleasing shape and appearance.

I claim:

The ornamental design for a crusher machine casing as shown and described.

JOSEPH L. HILLER.
